C. D. RICHARD.

MILEAGE REGISTER,

APPLICATION FILED JUNE 28, 1916.

1,362,267.

Patented Dec. 14, 1920.

UNITED STATES PATENT OFFICE.

CHARLES DONAT RICHARD, OF NEW YORK, N. Y.

MILEAGE-REGISTER.

1,362,267.

Specification of Letters Patent. Patented Dec. 14, 1920.

Application filed June 28, 1916. Serial No. 106,466.

To all whom it may concern:

Be it known that I, CHARLES D. RICHARD, a citizen of the Republic of France, residing at New York city, in the county of New York and State of New York, have invented 5 certain new and useful Improvements in Mileage-Registers, of which the following is a specification.

This invention relates to mileage registers, 10 and has particular reference to a novel and practical improvement in the devices of the type referred to which are particularly designed to be carried by the hub of a vehicle wheel to register the number of miles traveled.

A primary object of the invention is to provide a mileage register having novel means for driving a counter or register of the rotary type. Although devices of this 20 character have been heretofore used, the same have not given the most satisfactory results on account of the fact that the relatively frail and diminutive mechanism necessary for driving the counter is easily put 25 out of order by the severe strains and shocks caused by the vibrations and movements of the wheel and axle. Accordingly, the present invention proposes to provide a mechanism that, although of a relatively diminutive character is substantial, reliable, and accurate in its operation, and protected 30 in the best possible manner from the damaging effects of the wheel and axle movements referred to.

A further object of the invention is to provide a construction which will keep oil or axle grease from entering the counter or register compartment. Heretofore considerable difficulty has been experienced in successfully accomplishing this result, although 40 various expedients have been utilized, but with the construction contemplated in the present invention, this difficulty has been overcome to a maximum extent.

With the above and other objects in view which will more readily appear as the nature of the invention is better understood, the same consists in the novel combination and arrangement of parts hereinafter more fully 45 described, illustrated and claimed.

A preferred and practical embodiment of the invention is shown in the accompanying drawings, in which—

Figure 1 is a horizontal sectional view of 50 the present invention.

Fig. 2 is a vertical sectional view thereof.

Fig. 3 is a detail end elevation of the counter and its driving mechanism.

Similar references designate corresponding parts throughout the several figures of 60 the drawings.

In carrying the present invention into effect it is proposed to utilize a substantially frusto-conical casing or shell 1, which is interiorly threaded as at 2 to fit over the hub 65 portion H of the vehicle wheel, while the opposite end is provided with an inspection opening or window 3 for exposing to view a suitable counter or register device 4. This counter device 4 is carried upon a supporting bracket 5 which includes a shaft 6 loosely journaled in a supporting plate or rotor 7.

This plate preferably includes a threaded coupling flange 8 for engaging with the threaded portion of the shell 1 to lock the 75 plate and cap together, and is also provided with an abutment shoulder 9 for contacting with a flat annular seat or ledge 10 formed on the interior of the casing. The body of the plate 7 is formed at its side opposite the 80 coupling flange 8 with a recess 11 for receiving the relatively fixed anchor disk or stator 12, which is rigidly fastened, as at 13, to the shaft 6 of the counter supporting bracket. This anchor disk is connected by means of 85 the resilient pin element 14 with the nut 15 on the axle A of the vehicle, and thus, the rotary counter 4 is held in a stationary position in the counter chamber C, since it is connected or coupled with the stationary nut 15 90 on the axle.

With further reference to the attaching plate or rotor 7, it will be observed that the same is so constructed to prevent the working of oil and grease from the axle housing 95 chamber B of the shell 1 into the counter chamber C. That is to say, the side wall of the recess 11 is provided with an annular packing receiving groove 16 for receiving a suitable fiber packing, while the side wall of 100 the recessed central portion 17 of the anchor disk or stator 12 is also provided with a groove 18 for holding a fiber washer. This recess 17 of the anchor disk snugly receives the collar 19 of the plate 7 which surrounds 105 a central packing cavity 20. This packing cavity is adapted to receive a suitable fiber or equivalent washer 21, which may be held in place by a threaded steel bushing ring 22, thus compressing the packing and affording 110 the greatest resistance possible to the entrance of lubricant into the counter chamber

C by way of the shaft 6. Owing to the tight fit of the shoulder 9 of the attaching plate 7 with the seat 10 of the shell, no oil can pass from the chamber B to the chamber C at 5 this point, and with the arrangement of packings above described, oil and grease are effectually prevented from reaching the counter along the shaft 6.

It will therefore be apparent that the 10 rotor element 7 and stator element 12 provide in effect an oil-proof partition. That is to say, owing to the formation of the rotor 7, which permits of the nesting of the stator 12 therein, and the numerous packing rings 15 interposed in the joint between the two, an oil proof partition is provided which effectively prevents oil and grease from the axle A entering the register chamber or compartment C.

20 As will be observed from Figs. 1 and 2 of the drawings, the attaching plate 7 rigidly carries on the face thereof, that opens into the counter compartment, a driving pinion 23. This pinion is adapted to actuate 25 the counter device 4, and to this end there is employed a pinion 24 which meshes with the pinion 23, and is mounted on one end of a worm shaft 25, having thereon a worm 26 which in turn meshes with a worm pinion 30 27 fastened on a counter actuating shaft 28. This counter actuating shaft is journaled in the offset arms 29 of the bracket 5 which supports the counter 4, and extends longitudinally of the counter, as shown in Fig. 35 1. The end of the shaft 28 opposite the pinion 27 is provided with a crank disk 30 having thereon an eccentrically mounted a pawl 32, while on the opposite side of the disk 30, on the shaft 28, is loosely mounted a check pawl 33, the free end of which, as shown in Fig. 2, engages the ratchet wheel 34 on the counter operating shaft 35 in such a way as to prevent the turning of the latter 45 backward. The said pawls 32 and 33 are connected by a spring 36, whereby both of the same will at all times engage the toothed periphery of the ratchet wheel 34.

50 With this arrangement, it will be clear that upon the rotation of the hub of the vehicle and the shell 1 of the device which is carried on the hub, the attaching plate 7 will also be rotated and carry with it the driving pinion 23. As the counter stands 55 still in the counter compartment C of the casing, the rotation of the pinion 23 will drive the pinions 24 which will in turn rotate the shaft 28 through the connections already described. The rotary movement of 60 the shaft 28 will cause the crank pin 31, ec-

centrically mounted on the disk 30, to rise and fall, and thus cause the pawl 32 to alternately be raised and lowered, whereby in its lifting movement it will engage the teeth of the ratchet disk to move the shaft 35 of 65 the counter. As the pawl 36 is loosely mounted on the shaft 28 and is movable about the same as an axis, the free end thereof will merely trail over the toothed periphery of the ratchet wheel under the influence 70 of the spring 36, and prevent the said wheel from moving backward as the pawl 32 is thrust down into position to engage one of the ratchet teeth.

From the foregoing description it will be 75 apparent that as the plate 7 is of relatively stout character and firmly held in the shell 1, the counter device is amply protected, while the resilient connection 14 between the anchor disk 21 and the nut 15 on the axle 80 will take care of any lateral thrusts of the axle and prevent the same from doing any damage to this part of the counter driving mechanism. Furthermore, the novel oil-proof construction of the attaching plate 7 85 is of much practical importance, since it effectually provides for the exclusion of oil from the counter compartment C, and prevents the window 3 from being covered with oil and thus obscuring the indicia of the 90 register.

Without further description it is thought that the many novel improvements of the device will be readily recognized, and it will, of course, be understood that changes in the 95 arrangement and minor details of construction may be resorted to without departing from the spirit of the invention or scope of the appended claim.

100 I claim:

An oil-proof partition for hub-odometers including a rotor element having an external threaded portion and a stator receiving recess provided with a packing holding cavity in its side wall, and also having an internally 105 threaded collar located in the central part of the recess, packings arranged in the said cavity and in said collar, a threaded cap for entering the collar to hold said packing in position, and a stator plate nesting in said 110 recess of the rotor element and formed with a socket for receiving said collar, and also having a packing holding groove in the side wall of said socket.

In testimony whereof I hereunto affix my 115 signature in the presence of two witnesses.

CHARLES DONAT RICHARD.
